UNITED STATES PATENT OFFICE

162,865

CHAIR

Fred W. Niemann, Chicago, Ill.

Application November 15, 1949, Serial No. 6,041

Term of patent 3½ years

(Cl. D15—1)

To all whom it may concern:

Be it known that I, Fred W. Niemann, a citizen of the United States, residing at Chicago, State of Illinois, have invented a new, original, and ornamental Design for Chairs, of which the following is a specification, reference being had to the accompanying drawing, forming a part hereof.

The figure is a perspective view of a chair showing my new design.

I claim:

The ornamental design for a chair, as shown.

FRED W. NIEMANN.
